UNITED STATES PATENT OFFICE.

ALEXANDER LAUBSCHER, OF BRIDGEPORT, CONNECTICUT, ASSIGNOR TO THE WHEELER & WILSON MANUFACTURING COMPANY, OF BRIDGEPORT, CONNECTICUT, A CORPORATION OF CONNECTICUT.

HEMMER ATTACHMENT FOR SEWING-MACHINES.

SPECIFICATION forming part of Letters Patent No. 753,891, dated March 8, 1904.

Application filed January 23, 1900. Serial No. 2,448. (No model.)

To all whom it may concern:

Be it known that I, ALEXANDER LAUBSCHER, a citizen of the United States, and a resident of Bridgeport, in the county of Fairfield and 5 State of Connecticut, have invented certain new and useful Improvements in Hemmer Attachments for Sewing-Machines, of which the following is a specification.

My invention comprehends a combined 10 guide, folder, and hemmer for sewing-machines, and has for its object the production of a device which shall be simple in construction, yet effective in operation, and capable of automatically folding an undeturned hem 15 upon the cut or raw edge of the material for a shirt-bosom around and inclosing the edge of an underlying interlining in the manufacture of shirt-bosoms preparatory to sewing them upon shirts.

20 In the accompanying drawings, which form a part of this specification, Figure 1 represents a perspective view of the folder of my apparatus as looked at from above; Fig. 2, the same when viewed from below; Fig. 3, the 25 interlining-support; Fig. 4, the base-plate; Fig. 5, a side elevation; Fig. 6, an end elevation, and Fig. 7 a perspective view of the apparatus complete. Fig. 8 is an exaggerated cross-section of fabric, illustrating the fold 30 made by the device of this invention.

All figures show parts somewhat enlarged, the better to show their construction.

The folder which I employ is constructed of sheet metal and is shaped somewhat like 35 the scroll of a binder used on sewing-machines, as shown at A in Fig. 1. The upper lip a of the folder is not, however, provided with a return-bend, as in binders, but projects into space in order that the overlying material for 40 the shirt-bosom may pass beneath and enter the guiding passage-way a^4 , by the convolutions of which it is turned first downward and inward and again upward and outward, as in the formation of a hem, as it advances toward 45 the delivery end of the folder. While the upper lip a is continuous from the entrance to the delivery, the lower lip is so divided as to practically constitute two members, as shown at a^2 and a^3 , both of which are turned

inwardly to form a continuous passage-way 50 and guide, the entrance to which is shown at the point where is located the reference character a^4 for the undeturned edge of the bosom; but the portion a^2 not only extends inwardly far enough to form such guide, but is continued upwardly and outwardly and also toward the tip a' of the folder to serve as a support for the edge of the bosom and keep it separated from the underlying lining of the same. As a support for the underlying lining of the bosom I construct a plate, as shown at b , (see Fig. 3,) having a depending angle b' , and attach the same beneath the lip a^2 , with said angle portion secured to the lower and inwardly-turned lip a^3 and its straight edge 65 secured to the concave surface of the outwardly-turned lip a^2 , as seen in Fig. 5.

As a means of attaching the folder and guide to the sewing-machine, the convex surface of the folder A is secured to the member C, 70 which I will term the "base-plate," as shown in Fig. 4, which is provided with an orifice for the passage of a screw by means of which the base-plate is secured to the bed-plate of the sewing-machine in such relation to the needle 75 that the latter will puncture the upper ply, the lining, and the under ply and lay the stitches at a uniform distance from the undeturned edge of the bosom.

What I claim as my invention, and desire to 80 secure by Letters Patent, is—

1. A sewing-machine hemmer attachment, comprising a folder having an upper folding and guiding lip, and a divided lower lip to hem-fold the edge of an outer fabric, such as 85 a shirt-bosom, around and inclosing the edge of an underlying fabric or lining, a plate arranged between the members of the divided lower lip and adapted to support and guide the underlying fabric, and means for supporting said folder in operative position.

2. A sewing-machine hemmer attachment, comprising a folder having an upper folding and guiding lip, and a divided lower lip having a fabric passage-way between its members 95 to turn one piece of cloth around another in the form of an undeturned hem, said lower lip having two members arranged in differ-

ent planes, a plate attached to the lower member and beneath the upper member of the divided lower lip to support and guide the inner fabric, and a base-plate, substantially as described.

3. A sewing-machine hemmer attachment, comprising an upper folding and guiding lip a having a free edge projecting into space, a divided lower lip composed of members a^2 and a^3 arranged in different planes, with a passage-way between them, a plate b arranged between

the members of the divided lower lip and attached to the member a^3 thereof, and a base-plate.

Signed at Bridgeport, in the county of Fairfield and State of Connecticut, this 22d day of January, A. D. 1900.

ALEXANDER LAUBSCHER.
